(57) **CLAIM**

The ornamental design for a dental punch instrument for clear plastic aligners, as shown and described.

DESCRIPTION

FIG. 1 is a perspective view of a dental punch instrument for clear plastic aligners in an open position showing our new design.

FIG. 2 is a top view thereof in a closed position.

FIG. 3 is a bottom view thereof in the closed position.

FIG. 4 is a left view thereof in the closed position. A right view is a duplicate of the left view and is not included herein.

FIG. 5 is a front view thereof in the closed position.

FIG. 6 is a rear view thereof in the closed position.

FIG. 7 is a rear oblique view thereof in the closed position; and,

FIG. 8 is a front oblique view thereof in the open position. The dash-dot-dash broken lines define the boundaries of the claimed design. The even spaced broken lines shown in the drawings are included for the purpose of illustrating environmental structure and form no part of the claimed design.
